Primary Examiner — Antoine D Davis(74) *Attorney, Agent, or Firm* — Michael Best & Friedrich LLP(57) **CLAIM**

I claim the ornamental design for an accessory interface for a tool, as shown and described.

DESCRIPTION

FIG. 1 is a perspective view of an accessory interface.
 FIG. 2 is a front view of the accessory interface shown in FIG. 1.
 FIG. 3 is a rear view of the accessory interface shown in FIG. 1.
 FIG. 4 is a top view of the accessory interface shown in FIG. 1.
 FIG. 5 is a bottom view of the accessory interface shown in FIG. 1.
 FIG. 6 is a left side view of the accessory interface shown in FIG. 1; and,
 FIG. 7 is a right side view of the accessory interface shown in FIG. 1.
